UNITED STATES PATENT OFFICE.

ANNA C. DUNCAN, OF KANSAS CITY, MISSOURI.

DESIGN FOR A PIANO-CASE.

SPECIFICATION forming part of Design No. 22,188, dated January 31, 1893.

Application filed May 31, 1892. Serial No. 435,072. Term of patent 3½ years.

To all whom it may concern:

Be it known that I, ANNA C. DUNCAN, a citizen of the United States, residing at Kansas City, in the county of Jackson and State of Missouri, have invented and produced a new and original Design for a Piano-Case, of which the following is a full, clear, and exact description, reference being had to the accompanying drawing, forming a part thereof.

5 The figure is a perspective view of a piano-case embodying my design.

The design consists in the novel configuration of the case herein shown, the same being curved longitudinally so as to present, when viewed from top or bottom, substantially a

crescent-shape, the outer edge 1 and the ends being rounded, as is also the inner edge, which latter is designated by the numerals 8 and 10. Beneath the crescent-shaped case vertical bodies 2 and 3 are located, and present to the eye an irregular outline.

20 What I claim is:

The design for a piano case, as herein shown and described.

25 In testimony whereof I affix my signature in the presence of two witnesses.

ANNA C. DUNCAN.

Witnesses:

HARRIET E. PRICE,
JNO. L. CONDRON.
